US00D551835S

(12) **United States Design Patent** (10) Patent No.: **US D551,835 S**
(45) Date of Patent: **** Oct. 2, 2007**

(54) **INSOLE**

(75) Inventor: **Chak Wa Hung**, Hong Kong (HK)

(73) Assignee: **Rongyi Cai**, Markham, ON (CA)

(**) Term: **14 Years**

(21) Appl. No.: **29/264,430**

(22) Filed: **Aug. 10, 2006**

(51) LOC (8) Cl. **02-99**

(52) U.S. Cl. **D2/961**

(58) Field of Classification Search **D2/946, D2/961; 36/43, 44, 31, 145-182**

See application file for complete search history.
